UNITED STATES PATENT OFFICE

136,558

DESIGN FOR A WRIST WATCH STRAP

Harold J. Searer, Akron, Ohio

Application August 7, 1941, Serial No. 102,717

Term of patent 14 years

To all whom it may concern:

Be it known that I, Harold J. Searer, a citizen of the United States, residing at Akron, in the county of Summit and State of Ohio, have invented a new, original, and ornamental Design for a Wrist Watch Strap, of which the following is a specification, reference being had to the accompanying drawing, forming a part thereof.

Fig. 1 is a top plan view of a wrist watch strap showing the new design;

Fig. 2 is a side elevation thereof; and

Fig. 3 is a bottom plan view of the strap.

What is claimed is:

The ornamental design for a wrist watch strap, substantially as shown.

HAROLD J. SEARER.
